Charles G. Mollan
By Chase Gillman
Atty.

UNITED STATES PATENT OFFICE.

CHARLES G. MOLLAN, OF CHICAGO, ILLINOIS.

HAND-LAMP AND SIGNAL.

1,268,040.

Specification of Letters Patent. Patented May 28, 1918.

Application filed March 12, 1917. Serial No. 154,246.

To all whom it may concern:

Be it known that I, CHARLES G. MOLLAN, a citizen of the United States, and resident of Chicago, in the county of Cook and State of Illinois, have invented certain new and useful Improvements in Hand-Lamps and Signals, of which the following is a specification.

This invention relates to improvements in lamps, and has particular relation to electrically illuminated hand lamps to be used in connection with automobiles or motor driven vehicles, mainly for giving signals, and it consists in certain peculiarities of the construction, novel arrangement, combination and operation of the various parts thereof, as will be hereinafter more fully set forth and specifically claimed.

As it well known, many State, cities and towns have passed and strictly enforced laws and ordinances requiring chauffeurs and others in charge of, or occupying automobiles or motor-driven vehicles, to give certain signals, for instance, the direction in which the machine or vehicle is about to turn, by extending a hand at one side of the vehicle.

To fully meet this requirement by providing a hand-lamp and signal, which can be readily placed or worn on the hand so as to illuminate the latter, to the end that it may be readily seen when extended and the proper signals given at night or in darkness, is the principal and general object of the invention. Another object thereof, is, to provide a device of the above-named general character, which shall be extremely simple and inexpensive in construction, strong, durable, light, compact in form and efficient in operation, with its parts so made, that it can be readily attached to and disconnected from a suitable source of light.

Still another object is to provide the lamp casing with a hand engaging strap or device of such construction that it will automatically adjust itself to hands of different sizes, yet will securely hold the lamp in place on the hand in such a manner that the hand can be used for performing ordinary functions without impediment.

A further object of the invention is to provide means for locking the cap or cover of the lamp casing so that the sign carried by the former may be properly positioned

for legibility when the lamp is in use on the hand.

In the accompanying drawing which serves to illustrate an embodiment of the invention,

Figure 1, is a face view of the lamp showing it on the back of a hand, which hand is illustrated by dotted lines.

Fig. 2, is a sectional view taken on line 2-2 of Fig. 1, looking in the direction indicated by the arrows.

Fig. 3, is a sectional view through the casing of the lamp looking in the direction indicated by the arrows.

Fig. 4, is an enlarged detail view of a portion of the lamp casing and its cover showing means for preventing the movement of said cover or cap in the opposite direction on the casing.

Fig. 5, is a sectional view taken on line 5-5 of Fig. 4, and

Fig. 6, is a view in elevation, illustrating a part of the lamp casing and a modified form of the hand engaging device.

Like numerals of reference, refer to corresponding parts throughout the different views of the drawings.

The reference numeral 10 designates the casing or container which is preferably made of metal and cylindrical in shape as shown. The back 11 of the casing 10 is slightly curved inwardly and transversely with respect to the cylindrical portion of the casing to correspond with the curvature of the back of the hand. The opposite end of the casing is closed by means of a cap or cover 12 which is provided with a central opening 13 in which is fitted an open ring 14 which is preferably made of sheet metal and has on its outer portion a flange 15 which is bent inwardly at its outer edge to engage a piece of glass or a jewel 16, which is by preference colored, usually red. The wall of the casing 10 has extended through a suitable opening therein a lamp socket 17 in the inner end of which is fitted an incandescent lamp 18 of the ordinary or any preferred construction. The socket 17 is suitably secured in the opening within the wall of the casing 10 in any suitable manner and is provided in its outer portion with a pair of oppositely disposed V-shaped slots 19 for the reception of pins 20 mounted on the opposite sides of a switch plug 21 which has

connected thereto an electric conductor 22 leading to a supply of electricity not shown. The connections made by the switch plug 21 through the socket 17 with the lamp 18 are of the ordinary or any well known kind, and it is deemed unnecessary to herein describe the same in detail. Secured to the outer surface of the back 11 of the lamp casing and at diametrically opposite points are the ends of a resilient strap or hand engaging device 23 which as clearly shown in Fig. 2 of the drawing, is in the form of a curved or segmental loop which has its ends slightly enlarged. The ends of the strap 23 are by preference secured to the back 11 of the casing by means of brads or rivets 24 so as to hold the strap or hand engaging device diametrically across the casing. By employing this construction of a strap it is obvious that the inwardly bent portion thereof will impinge against the palm of the hand, so as to hold the back 11 of the casing in contact with the back of the hand, yet in such a way that the hand may be used without material impediment or obstruction, and it is also evident that on account of the resiliency of the strap 23 it will adjust itself to hands of different sizes. The wall of the casing 10 is provided on its outer surface 29 near its free end with a pair of pins 25 and 26 which project outwardly and are located diametrically opposite each other, as is clearly shown in Fig. 3 of the drawing. These pins are employed for engagement with the cap or cover 12 and are used for the purpose of securely holding said cover in position on the casing after the cover has been properly adjusted on the latter. As is clearly shown in Figs. 2 to 5 inclusive of the drawings, the cover 12 is provided with a peripheral and inturned flange 27 which is slightly larger than the circular wall of the casing and has its main portion spaced therefrom at a sufficient distance to permit the pins 25 and 26 to move between it and the wall of the casing on which they are mounted. At a suitable point the flange 27 of the casing is provided with a recess or cutaway part 28 and one edge of said recess is inturned as at 29, (see Fig. 5 of the drawing.) The cap or cover 12 may be provided around the ring or holder 15 for the window or transparent jewel 16 with openings 30 in the form of letters, figures or characters, to 55 form a sign or signs. In the present instance the openings 30 are shown in the form of letters, and spell the words "Safety first", but it is evident that any other suitable sign may be employed. Fitted on the inner sur-

face of the cap or cover 12 is a sheet of 60 transparent material 31, such as celluloid or the like.

In Fig. 6 of the drawing, a modification in the construction of the hand engaging device is illustrated, which consists in employing an elastic strap 32 which is secured at its ends by means of loops 33 or otherwise, to apertured brackets 34 which are soldered or otherwise fastened to the back 11 of the casing at diametrically disposed points. 70

In placing the cover on the casing, one of the pins, say the pin 25, is placed under the inturned edge of the flange 27 at a point diametrically opposite the recess 28 in said flange, when by pressing the cover on the 75 casing it is obvious that the pin 26 will pass through the recess 28 when by turning the cover or cap 12 in the opposite direction from the inclination of the inclined portion 29 of said flange until the pin 25 reaches said inclined part as shown in Fig. 5 of the drawings, the cap will be prevented being turned further in the same direction, thus the sign will be displayed in the proper position to be legible, as the pins 25 and 26 80 are located at proper points for this purpose.

Having thus fully described my invention, what I claim as new and desire to secure by Letters Patent is—

1. A signal lamp comprising a casing, a cap or cover detachably and revolvably mounted on the casing and having sign forming openings therein, means to limit its rotation in one direction, a lamp within the 85 casing and a hand engaging device carried by the casing.

2. A signal lamp comprising a casing, a window in the casing and a resilient hand strap extended across and carried by the casing, said strap having loops at its ends and bowed inwardly between its ends. 100

3. A signal lamp comprising a portable casing having an inwardly curved wall to fit the back of a human hand, a cap or cover 10 detachably mounted on the casing and having sign forming openings therein, means to fix said cover on the casing in such a position as to render the said sign forming openings legible when the lamp is in use on 11 the hand, a lamp within the casing, and a hand engaging device carried by the casing cross-wise the curved wall thereof.

CHARLES G. MOLLAN.
